John Siddons & James C. Hart, of Rochester, N.Y.
Letters Patent No. 1245 Dated May 15, 1860.

The Schedule referred to in these Letters Patent and making part of the same.

To all whom it may concern:

Be it Known that we John Siddons & James C. Hart, of the City of Rochester, in the County of Monroe and State of New York, have made and invented a certain new and ornamental design for a top plate for a stove; we do hereby declare the following to be a full description thereof of reference being had to the accompanying drawings, making part of this Specification of which

Figure 1. is a plan of one half of the plate.

Figure 2. is a detailed drawing of the ornamental figure and.

Figure 3. is a section of the plate.

This design consists of a certain arrangement of heads & cyma reversa as is shown in the drawings, the cyma reversa at A, figure 3, having the ornamental figure (figure 2) arranged thereon as seen in figure 1.

The construction of the plate will be readily understood from an inspection of the section figure 3.

What we claim as our design and desire to secure by Letters Patent is the Stove plate shown in the drawings and consisting of the arrangement of heads, cyma reversa, and ornamental figures therein exhibited.

End Witnesses.
